STOCKING

Leon W. Zylberberg, Norristown, Pa.

Application September 27, 1951, Serial No. 16,764

Term of patent 3½ years

(Cl. D47—7)

To all whom it may concern:

Be it known that I, Leon W. Zylberberg, a citizen of Poland, residing at Norristown, in the county of Montgomery and State of Pennsylvania, have invented a new, original, and ornamental Design for a Stocking, of which the following is a specification, reference being had to the accompanying drawing, forming part thereof.

Fig. 1 is a side elevation of the stocking embodying my new design; and

Fig. 2 is a fragmental rear view thereof.

I claim:

The ornamental design for a stocking, substantially as shown.

LEON W. ZYLBERBERG.
